UNITED STATES PATENT OFFICE

VIRGILIO FRASCHETTI, OF LONDON, ENGLAND

CABINET FOR THE STORAGE OF GRAMOPHONE DISK RECORDS AND THE LIKE

Application filed April 25, 1929, Serial No. 358,086, and in Great Britain May 17, 1928.

This invention relates to improvements in connection with cabinets for the storage of gramophone disk records and the like of the kind divided into a number of compartments 5 in each of which a record may be filed in a vertical position resting on a movable base which can be tipped by means of an exterior operating member (one for each compartment) to cause the record to move and project at the front of the cabinet to facilitate extraction. Herein, where the description permits, the term "record" is used for convenience to include other disk-like objects which could, with advantage, be stored in a 15 cabinet according to the invention.

The invention concerns an improved construction and arrangement directed particularly to the the movable base of each compartment and its associated operative device. 20 In carrying out the invention, the body of the cabinet is divided at the front only, or, if desired, from front to back, by a plurality of spaced-apart vertical partitions, into a suitable number of record divisions or compartments. Each of the said divisions is of 25 a suitable height and width to accommodate a record, and the vertical partitions, or the front portions thereof, are erected between upper and lower frames or other suitable 30 rigid structures. The lower frame may have front and rear edges arranged to form, at its top, a cradle which may be notched or V-cut at each compartment to guide the record. In this connection the said frame may have

35 along its rear edge an upstanding rubber strip which is V-notched at each compartment, the records being adapted to tip or balance over the said strip after being projected forwardly and drop into the cradle, whereby 40 they are prevented from falling from the front of the cabinet or back on to the movable base. The lower frame is supported on the floor of the cabinet or other suitable fixed base. The depth from the back vertical edges 45 of the partitions is optional and may be such that the records either project out at the front a requisite distance or have their front edges residing behind the front edges of the said partitions.

50 The front edges of the partitions need

not necessarily be vertically straight but can be shaped in any suitable fashion, ornamental or otherwise.

Underneath the base, between a pair of longitudinal parallel frames or strips forming parts of the aforesaid lower frame and secured to the base, are disposed a plurality of plungers, one for each compartment, transversely disposed with relation to the cabinet body, i. e. aligned with the respective planes of the compartments. The said plungers may be located in guide tubes fixed between the aforesaid parallel strips or frames, the front ends of the plungers projecting in front of the body, and having knobs or equivalent extremities, and the rear ends being arranged to operate the movable base members. 55 60 65

The movable base members are pivoted devices controlled by the plungers, being of crank or bell-crank formation and pivoted on a common pivot rod extending throughout the length of the cabinet. In some embodiments of the invention, the plunger rods are connected to said cranks between the axis about which they swing and the record-holding portions, in which case, the plungers are adapted to be pulled out in order to forwardly project the records. 70 75

In another arrangement wherein the plungers are adapted to be pressed in, in order to forwardly project the records the tails of the cranks are disposed pendant-wise, the plunger rods being connected to the said tail cranks below the axis about which said cranks swing. 80 85

In each of the foregoing arrangements the portion of the crank on which the record is supported is substantially horizontal to support the record on its upper edge, and is virtually the movable base above referred to. The cranks may be of plywood or other suitable material thick enough to fill the space between adjacent partitions, whilst being an easy moving fit therebetween. The upper edge thereof may be scolloped or curved to fit the periphery of the record and may have one, two or any other suitable number of pairs of upwardly extending springly clips of whalebone or the like to grip the record. 90 95

The part of the record resting on said movable base is that towards the rear of the cabi- 100

net body, and, in operation, by pressing in an appropriate plunger, the movable base (part of the crank) is swung upwardly and the record forwards. A resilient buffer may be arranged along the front of the compartments or elsewhere to prevent damage to records thrown out by the movement, which may form the front edge of the lower frame hereinbefore described.

10 The device as described so far and termed the cabinet body is or may be covered by an exterior casing, i. e. sides, back and top, and hinged doors.

15 The movable base may, in a modification, be mounted by parallel linkage or by pin-and-slot arrangements or other device on to what has been termed the tail member so that it can receive a degree of reciprocation instead of or in addition to the oscillation hereinbefore described.

20 In a further modification, the crank may carry at its upper end a grooved sheave adapted to have rolling contact with the record, in which case a fixed false floor will be provided for supporting the records when stored in the cabinet or a plurality of equivalent fixed supports.

25 In a still further modification, the movable base is hinged or pivoted to the rear edge of a fixed member or part of the structure, and each plunger rod carries at its innermost end a sheave which is adapted to ride along the undersurface of the said movable base and swing same upwardly as the said sheave travels forwardly by manipulating the appropriate plunger rod.

30 The invention will be the more readily understood by referring to the accompanying drawings illustrating practical embodiments 40 of the invention, and wherein:—

Figure 1 is a vertical cross-section through one form of apparatus in accordance therewith.

45 Figure 2 is a detail hereinafter described; and,

Figure 3 is a cross-section on line α , α in Figure 1.

50 Figures 4-6 are fragmentary sectional views of modifications hereinafter described.

55 Referring firstly to Figure 1 of the drawings, the apparatus comprises a cabinet 1 having a floor 2 and a hinged door 3. Upon the floor 2 at the front of the cabinet is mounted a lower frame consisting of spaced-apart uprights 4 and 5 arranged parallel to one another and extending along the full length of the cabinet, upon which is mounted a horizontal platform 6.

60 A plurality of plunger rods 7 arranged under the platform 6 are slidably mounted in the two walls 4 and 5 with respect to which they are transversely disposed, each of said plunger rods being bent or cranked so that at their outer ends the rods are al-

ternately arranged in different planes, i. e. in two rows. Operating knobs or buttons 8 fixed on the ends of the rods project from the front of the wall 2.

65 Each of the rods 7 is pivotally connected at its rear end to a tipping member 9, the assembly of tipping members being fulcrumed on a common rod 10 extending throughout the length of the cabinet. Each tipping member at its rear upper portion forms a seating for a record, being arcuate-shaped to conform approximately with the outer contour thereof, and is grooved, as shown in cross-section in Figure 3. The tipping members are adapted to rest upon the support 11 which extends along the full length of the cabinet.

70 The action of pulling out a plunger causes the appropriate tipping member 9 to swing up to the position shown in dotted lines in Figure 1, such upward movement being limited by a ledge 12, and such movement of the member 9 moves the record in an upward and forward direction, the record swinging about an upstanding resilient strip 13 secured along the back edge of the platform 6. The degree of forward movement thus imparted to the record is such that the centre of gravity of the latter will pass from behind to in front of the strip 13, with the result that the record, due to its own weight, will become seated in a cradle formed by the strip 13 and a front resilient buffer strip 14 secured along the front edge of the platform 6, the strip 14 serving to prevent the record falling out at the front and being so arranged in relation to the strip 13 as to maintain the records out of contact with the platform 6. The strip 13 is formed with a plurality of notches, one to each record, as shown in Figure 2, which is a front elevation of the strip, and said strip 13 also forms a front support to the records when same are stored in the cabinet and resting upon the tipping members 9.

75 Partitions 15 which are spaced-apart a sufficient distance to permit free movement between them of a record, are erected upon the platform 6 between the latter and an upper frame or structure 16. Narrow partitions 17 extend from the main partitions 15 back to the support 11 and serve as guides for the movement between them of the tipping members 9.

80 The partitions 15 may be of solid material, e. g. wood, or, alternatively, could be formed by front and rear wire frames covered with cloth or other suitable fabric stretched between them. In this connection each wire frame could be of sinuous form, extending vertically upwards then horizontally for spacing purposes, then vertically downwards, then horizontally for the next space, then vertically upwards and so on, the cloth being

of sleeve form to embrace the frames and following the configuration thereof.

If desired, the partitions 15 may be inclined with respect to one another so that the record space between them decreases from 6 the front to the back in each case.

Figure 4 illustrates a modification wherein the plunger rods 7 are connected to the tipping members 9 below the axis of swinging of the latter (shown at 10), a push being imparted to said plunger rods in this case in order to forwardly project a record, instead of a withdrawing action as in the above-described construction.

15 In the further modification shown in Figure 5, each plunger rod 7 is pivotally connected at its rear end to a swinging arm 18 which at its upper end is furnished with a grooved sheave 19 which has rolling contact 20 with the periphery of the record. In this construction, the records, when being stored, seat upon a fixed floor 20 having a curved upper surface, said floor being equivalent to the ledge 12 shown in Figure 1.

25 In the further modification shown in Figure 6, the tipping members 9 are hingedly connected to a fixed part 21 corresponding to the ledge 12 in Figure 1, and a sheave or roller 22 mounted on the inner end of each 30 plunger rod is adapted to travel along the bottom surface of the appropriate member 9 and in so doing cause said member to tilt.

I claim:—

1. In a record storage cabinet, front and 35 rear uprights, front and rear strips supported by said uprights forming a record cradle, a pivoted tipping member located behind the rear upright cooperating with the rear strip to form a record seat, a rod for effecting pivotal movement of said tipping member to shift a record from said record seat across said rear strip to said record cradle, said rod being pivoted to said tipping member and extending through and being supported by 45 said front and rear uprights, and a stop member extending rearwardly from the rear upright to be engaged by the tipping member to limit swinging movement of the latter in a direction to effect shifting of a record from 50 the record seat to the record cradle.

2. In a record storage cabinet, front and rear uprights, front and rear strips supported by said uprights forming a record cradle, a pivoted tipping member located behind the 55 rear upright cooperating with the rear strip to form a record seat, said tipping member having a groove to receive an edge portion of a record and the base of said groove being curved to conform substantially to the curvature of the edge of the record.

In testimony whereof I have affixed my signature hereto this 15th day of April, 1929.

VIRGILIO FRASCHETTI.
